TEN-SIDED DIE

David Reader, New York, N. Y.

Application September 22, 1951, Serial No. 16,711

Term of patent 14 years

(Cl. D34—5)

To all whom it may concern:

Be it known that I, David Reader, a citizen of the United States and a resident of the county of Bronx, city and State of New York, have invented a new, original, and ornamental Design for a Ten-Sided Die, of which the following is a specification, reference being had to the accompanying drawing, forming part hereof and in which:

Fig. 1 is a top plan view of a ten-sided die showing my design.

Fig. 2 is a bottom plan view.

Fig. 3 is a side elevational view taken upon the line 3—3 of Fig. 1.

Fig. 4 is a side elevational view taken upon the line 4—4 of Fig. 1.

Fig. 5 is a side perspective view.

The dominant features of my design are shown in solid lines.

I claim:

The ornamental design for a ten-sided die, as shown and described.

DAVID READER.
